UNITED STATES PATENT OFFICE

148,919

DESIGN FOR FOOD TONGS

Callie Duncan, The Dalles, Oreg.

Application September 4, 1946, Serial No. 133,055

Term of patent 14 years

(Cl. D44—4)

To all whom it may concern:

Be it known that I, Callie Duncan, a citizen of the United States, residing at The Dalles, in the county of Wasco and State of Oregon, have invented a new, original, and ornamental Design for Food Tongs, of which the following is a specification, reference being had to the accompanying drawing, forming part thereof.

The figure is a perspective view of food tongs, showing my new design.

I claim:

The ornamental design for food tongs, as shown.

CALLIE DUNCAN.
